Frank S. Busser
ATTORNEY.

UNITED STATES PATENT OFFICE.

EDWARD A. HILL, OF PHILADELPHIA, PENNSYLVANIA, ASSIGNOR TO A. T. BAKER AND COMPANY, OF PHILADELPHIA, PENNSYLVANIA, A CORPORATION OF PENNSYLVANIA.

YARN-MEASURING DEVICE.

Application filed July 13, 1923. Serial No. 651,308.

To all whom it may concern:

Be it known that I, EDWARD A. HILL, a citizen of the United States, residing at Philadelphia, county of Philadelphia, and State of Pennsylvania, have invented a new and useful Improvement in Yarn-Measuring Devices, of which the following is a full, clear, and exact description, reference being had to the accompanying drawings, which form a part of this specification.

My invention relates to mechanism for measuring yarn and more particularly for measuring yarn as it is transferred from one support to another, as, for example, from a spool to a bobbin.

In the winding of yarn, for example, onto a bobbin or spindle for use in supplying yarn to a loom, it is highly advantageous for all the spindles or bobbins to have on them, as nearly as possible, the same yardage of yarn in order that, in the case of spindles, the yarn will become exhausted from all the spindles in a given loom at the same time, or, in other words, to avoid the exhaustion of yarn from any spindle before the remaining spindles become exhausted and thus avoid the production of faulty goods.

Yarn is ordinarily purchased by the pound wound on spools, and it is necessary, in weaving for example, that desired quantities be transferred to spindles and bobbins which are placed in a loom and supply thread for the weaving operation.

Heretofore the winding of yarn onto a spindle or bobbin has been accomplished in a winding machine, the thread of yarn being passed from the supply through a tension device and to the spindle, through a reciprocating member, which serves to guide the yarn so that it will be wound evenly. The winding is continued until the spindle and yarn wound on it has reached a certain size, whereupon a trip mechanism is actuated to break the driving connection with the spindle and the winding ceases. Such method results in wide variations in the yardage of yarn wound on different spindles, due to variation in tension and other causes, with the result that the several spindles in a loom vary widely in the amount of yarn they contain, and in order to avoid the production of imperfect goods, because of certain spindles running out before others, all the spindles are replaced before any of them

run out and the yarn remaining on them re-wound on fresh spindles.

Thus, for the impracticability of winding spindles with uniform yardage, waste results in the production of imperfect goods, or the expense of production is considerably increased by the necessity for rewinding yarn remaining on spindles replaced before they are substantially exhausted.

Various devices have been tried with a view to measuring and controlling the yardage of yarn wound, but such devices have proved inaccurate or of such complication and delicacy as not to warrant their use.

Now it is the object of my invention to provide a device whereby yarn may be measured as it is wound and whereby when a predetermined yardage is wound the thread will be cut.

Further objects of my invention are to provide a device which will be simple and inexpensive to manufacture, highly accurate in operation, and which will be foolproof and require substantially no adjustment.

Having now indicated in a general way the nature, purpose and advantages of my invention, I will proceed to describe a practical embodiment thereof, in detail, with reference to the accompanying drawings, in which—

Fig. 1 is a plan view of a device embodying my invention with part of the casing removed.

Fig. 2 is a fragmentary plan view of the device shown in Fig. 1, partly broken away.

Fig. 3 is a sectional view on line 3—3, Fig. 1.

Fig. 4 is a sectional view on line 4—4, Fig. 2.

a represents a casing, adapted to support the various parts of the device, and provided with removable cover sections *b* and *c*.

d represents a wheel secured on the end of a shaft *e*, suitably supported by bearings in the casing, and carrying a worm *f* adapted to mesh with a worm wheel *g* carried by a shaft *h* extending at right angles to the shaft *e* and suitably supported by bearings in the casing. The bearings supporting the shafts *e* and *h* are inserted in, and may be removed from, the casing through apertures in the casing closed by plugs *i*.

Within the casing is superimposed posi-

tion are placed a pair of gears j and k , the lower gear j having one hundred teeth, the upper gear k having an extra or hunting tooth, that is, having one hundred and one teeth, and both gears being in mesh with a worm l on the shaft h . The lower gear j is fixedly secured to a dial m which is adapted to revolve with the gear, while the upper gear k is connected to a dial n , concentric with dial m , by means of a spring-pressed annular detent o adapted to engage in depressions in the under side of the dial n , whereby the dial n may be revolved by the gear k and at the same time 15 may be turned relative to the dial m without revolving gear k .

Between the dials m and n , and adjacent the periphery of dial n , is placed a ring p recessed as at q , Fig. 2, and supporting in 20 the recess a spring-pressed pivoted stop r one end of which is normally retained extended beyond the periphery of the ring and is adapted to contact with a fixed stop or 25 pin s on dial n and stop relative movement of the dials when the dial n is moved clockwise or to give and permit pin s to pass when dial n is turned counterclockwise. The wall of the ring p forms an internal gear t adapted to be engaged by a pinion u 30 secured to dial m by means of a pin v , the head of which is slotted permitting its rotation by means of a screw driver with consequent rotation of the pinion which results in rotation of the ring p enabling the stop r to be positioned, for the purpose to be hereinafter explained.

The gears and dials are centered about a pin w , being spaced from the bottom of the casing by a washer x and secured by a nut y . On the upper surfaces of the dials m and n are drilled holes z , z' , respectively, which, when they are aligned, are adapted to receive a pair of pins 2 , $2'$, depending from a U-shaped member 3 which embraces an arm 4 and is pivoted thereto adjacent its outer end. The inner end of arm 4 is secured to a forked lever 5 , which in turn is pivotedly carried by brackets 6 . A spring 7 , secured at one end to member 3 , wrapped 45 around a post 8 on member 3 and engaging a post 9 on arm 4 , acts to keep member 3 in line with arm 4 , but yieldingly permits the member to swing on its pivotal connection with the arm. A second spring 10 , an 50 end of which bears on the forked lever 5 , is wrapped around the pivot connecting the lever 5 with brackets 6 and tends to move the lever 5 , arm 4 and member 3 with its depending pins downwardly.

60 Pivotedly supported between its ends on the pivot supporting the forked lever 5 is a lever 11 , one end of which underlies lever 5 , Fig. 3, and the other end of which is adapted, under the influence of a spring 65 21 , to engage in a reduced section of a rod

12 slidably supported in brackets 13 and carrying at its end a member 14 adapted to cooperate with a knife 15 . A spring 16 surrounds the rod 12 and acting between one of the brackets 13 and a collar 17 secured to the rod tends to move the rod to effect the shearing of a thread between the member 14 and knife 15 , when the arm of lever 11 is withdrawn from the reduced section of the rod 12 .

70 Secured at one end to the collar 17 on rod 12 by a slot and pin connection is a link 18 , the other end of which is pivotally connected to one arm of a lever 19 pivoted to the casting. The other arm of lever 19 has secured 75 to it a piece of rubber 20 , which is adapted, when the rod 12 is released and moved under the action of spring 16 , to be moved by the turning of lever 19 , through link 18 , into contact with wheel d and act as a brake 80 thereon.

85 In the device as above described, the wheel d is made so that its perimeter measures three inches, or, in other words, that in the 90 passage over it of one yard of thread it will make twelve revolutions. The worm on shaft e and the worm wheel on shaft h are in the ratio of 24 to 1 so that the shaft h will make one revolution to every twenty-four revolutions of the shaft e and wheel d . The worm l is as one hundred to one and as 95 one hundred and one to one with the gears j and k , respectively. Therefore, for each one hundred revolutions of the shaft h , the gears j and k will make one revolution, but since the gear k has one more tooth than the gear j , it will lag behind the gear j , or in 100 other words, two points one on each gear, or on the dials m and n driven by the gears, if in line when the gears started would be 105 out of line when they had made one revolution, or, conversely, two points out of line by a distance equal to one tooth would be in line after one revolution of the gears, since gear k will make a distance of one tooth less than one revolution when gear j makes one full revolution. The size of the wheel d and the ratio between the worm and gear on the shafts e and h being given the dials m and n are calibrated so that when it is desired to utilize the device for measuring 110 yarn or thread being wound, the dials may be initially relatively adjusted so that the holes z , z' will be out of line a distance equivalent to one or more teeth on the gear k , which, having one more tooth than gear j , will in each revolution of the dials lag behind gear k a distance equal to one tooth and bring the holes in line after one or more revolutions of the gears and dials.

115 The device as above described may be attached to any form of winding machine by means of any suitable bracket, the device 120 preferably being so attached that the yarn or thread being wound will pass over the 125

wheel d and between the knife 15 and the member 14 in its travel from the tensioning device to the bobbin or spindle upon which it is being wound.

5 Assuming now that the device is in position and that the pins 2, 2' are entered in the holes z , z' in the dials m and n , the brake 20 being against the wheel d and member 14 being in cutting relation with the knife 15. If now it be desired to wind (say) two hundred yards of yarn or thread on a bobbin, the arm 4 is raised, withdrawing the pins 2, 2' from the holes z , z' and the rod 12 pushed against its spring to position the 10 reduced portion for the reception of the arm of lever 11, which drops onto the reduced portion and holds the rod set with the member 14 clear of the knife and the brake 15 free of the wheel d . While the arm 4 20 is held up, the dial n is turned in a clockwise direction relative to the dial m a distance of one tooth, which may be conveniently done with reference to a zero line marked on the casing, the dial being calibrated or graduated as shown, thus throwing the holes z , z' out of line. The arm 4 25 may then be lowered and the pins will rest on the surface of the dials maintaining the arm in a position free of the lever 11 which 30 will be held in position to retain rod 12, as shown in Fig. 1.

The yarn or thread to be measured is passed through any suitable tension device, then over the wheel d and over the rod 12 between the knife 15 and the member 14, as indicated by dotted line in Fig. 1.

The winding machine is then started and the traveling thread rotates the wheel, effecting a drive of the gears j and k and 40 rotation of the dials m and n . With the size of wheels and the gear ratios referred to for each revolution of shaft h , the wheel d will revolve twenty-four times and pass two yards of thread, and since one hundred 45 revolutions of shaft h will be required to revolve gears j and k once, it follows that when gears j and k are revolved once, wheel d will have turned twenty-four hundred times and will have passed two hundred 50 yards of thread. Now, since the gears were initially set with the holes z , z' out of line by a distance of one tooth and since one of the gears has one tooth more than the others, when the gears have made one revolution 55 the holes will be brought into line beneath the pins 2, 2'. Now arm 4 is pressed downwardly by its spring 10, and when the holes are in line the pins 2, 2' will drop into them, permitting arm 4 to move down to 60 contact with lever 11 raising it out of the reduced section of rod 12 and permitting spring 16 acting against collar 17 to move the rod to bring member 14 in cooperating 65 relation with knife 15 to sever the thread, at the same time acting on link 18 to turn

lever 19 on its pivot and bring brake 20 against the periphery of wheel d to stop it.

In the event that the momentum of the parts causes the gears to be slightly rotated after the thread is severed the member 3 carrying the pins 2, 2' will turn on its pivotal connection with arm 4 to accommodate for any movement of the dials m and n after pins 2, 2' have entered the holes z , z' , as shown in Fig. 2.

70 If now the device is to be used repeatedly for measuring the same yardage, the stop r may be adjusted, by rotating pinion u , as above described, to a position to cooperate with pin s on dial n and permit the gear k to be adjusted, after each length is measured and cut off, by merely turning dial n back until the pin strikes the stop.

75 The device above described may be utilized for measuring yardages up to twenty thousand with great accuracy, but it will be obvious that the device may be modified by changing the size of the wheel d , the gear ratios and the calibration of the dials m and n to provide for measuring any 80 yardages, without departing from my invention. Further, it will be noted that my invention is not limited to the measuring of yarn thread, but is equally adaptable for the measurement of any other material and that 85 the device may be adapted to effect stoppage of a winding mechanism after a given yardage is wound instead of effecting severance of the material being wound or to do both.

90 Having now fully described my invention, what I claim and desire to protect by Letters Patent is:

1. In a device for measuring thread, a measuring pulley adapted to be rotated by a traveling thread, a worm driven by said pulley, a pair of gears, one having more teeth than the other, driven by said worm, a pair of concentric dials, one of said dials being secured to one of the gears, means 105 forming a yielding connection between the other dial and gear, means cooperating with the surfaces of said dials for arresting the travel of the thread over said pulley and means for supporting the elements of the device in operative relationship.

110 2. In a device for measuring thread, a measuring pulley adapted to be rotated by a traveling thread, a worm driven by said pulley, a pair of gears, one having more teeth than the other, driven by said worm, a pair of concentric dials, one of said dials being secured to one of the gears, a detent 115 forming a driving connection between the other dial and gear, means controlled by said dials for arresting the travel of the thread over said pulley and means for supporting the elements of the device in operative relationship.

120 3. In a device for measuring thread, a 125

measuring pulley adapted to be rotated by a traveling thread, a worm driven by said pulley, a pair of gears, one having more teeth than the other, driven by said worm, a 5 dial driven by one of said gears, a dial concentric with said first mentioned dial driven by the other of said gears, said dials having depressions formed therein adapted to be brought into alignment, a cutter operative to 10 sever the thread traveling over said measuring pulley, means adapted to render said cutter inoperative, means including a pair of aligning pins adapted, when said depressions in said dials are in alignment, to drop 15 therein and release said cutter and means for supporting the elements of the device in operative relationship.

4. In a device for measuring thread, a measuring pulley adapted to be rotated by 20 a traveling thread, a worm driven by said pulley, a pair of gears, one having more teeth than the other, driven by said worm, a dial driven by one of said gears, a dial concentric with said first mentioned dial 25 driven by the other of said gears, said dials having depressions formed therein adapted to be brought into alignment, means operative to arrest the travel of the thread over 30 said pulley, means adapted to render said arresting means inoperative, means including a pair of aligning pins adapted when 35 said depressions in said dials are in alignment to drop therein and release said arresting means and means for supporting the elements of the device in operative relationship.

5. In a device for measuring thread, a measuring pulley adapted to be rotated by a traveling thread, a worm driven by said 40 pulley, a pair of gears, one having more teeth than the other, driven by said worm, a dial driven by one of said gears, a dial concentric with said first mentioned dial driven by the other of said gears, said dials 45 having depressions formed therein adapted to be brought into alignment, a cutter operative to sever the thread traveling over said measuring pulley, a brake operative to stop 50 said measuring pulley after the severance of the thread traveling thereover, means adapted to render said cutter and brake inoperative, means including a pair of aligning pins adapted when said depressions in 55 said dials are in alignment to drop therein and permit said cutter and brake to operate and means for supporting the elements of the device in operative relationship.

6. In a device for measuring thread, a measuring pulley adapted to be rotated by a 60 traveling thread, a worm driven by said pulley, a pair of gears, one having more teeth than the other, driven by said worm, a dial driven by one of said gears, a dial concentric with said first mentioned dial 65 driven by the other of said gears, said dials

having depressions formed therein adapted to be brought into alignment, a spring-actuated cutter operative to sever the thread traveling over said pulley, mechanism including a pair of aligning pins normally resting on the surface of said dials respectively to position said mechanism to render said cutter inoperative and adapted, when said depressions are in alignment, to drop 70 therein and permit release of said cutter and means for supporting the elements of the device in operative relationship.

7. In a device for measuring thread, a measuring pulley adapted to be rotated by a traveling thread, a worm driven by said 80 pulley, a pair of gears, one having more teeth than the other, driven by said worm, a pair of concentric dials driven by said gears respectively, a stop adjustable about the axis of one of said dials, a fixed stop on the other dial adapted to cooperate with said adjustable stop, means for arresting the travel of the thread over said pulley, means controlled by said dials for controlling said arresting means and means for supporting 85 the elements of the device in operative relationship.

8. In a device for measuring thread, a measuring pulley adapted to be rotated by a traveling thread, a worm driven by said 90 pulley, a pair of gears, one having more teeth than the other, driven by said worm, a pair of concentric dials, one of smaller diameter than the other, a fixed stop on the dial of larger diameter, a pivoted stop adjustable 95 about the axis of the dial of smaller diameter and adapted to pass said fixed stop in one direction of rotation of said smaller dial and engage therewith in the other direction of rotation of said dial, means to adjust 100 said pivoted stop, means controlled by said dials for arresting the travel of the thread over said pulley and means for supporting the elements of the device in operative relationship.

9. In a device for measuring thread, a measuring pulley adapted to be rotated by a traveling thread, a worm driven by said pulley, a pair of gears, one having more teeth than the other, driven by said worm, a pair of concentric dials, one of smaller diameter than the other, an internal gear provided with a recess in its periphery positioned between said dials, a stop extending beyond the periphery of said gear pivotally 115 mounted in the recess therein, a fixed stop on the dial of larger diameter, a pinion carried by said dial of smaller diameter and engaging said internal gear, means controlled by said dials for arresting the travel of the thread over said pulley and means for supporting the elements of the device in operative relationship.

10. In a device for measuring thread, a measuring pulley adapted to be rotated by a 120

traveling thread, a worm driven by said pulley, a pair of gears, one having more teeth than the other, driven by said worm, a dial, a yielding driving connection between 5 said dial and one of said gears, a dial of smaller diameter than, and concentric with, said first mentioned dial driven by the other gear, a stop adjustable peripherally of said dial, means carried by said dial for adjusting said stop, a fixed stop on said first mentioned dial adapted to cooperate with said adjustable stop, means for arresting the travel of the thread over said pulley, means controlled by said dials for controlling said 10 arresting means and means for supporting the elements of the device in operative relationship.

11. In a device for measuring thread, a measuring pulley adapted to be rotated by a traveling thread, a worm driven by said pulley, a pair of gears, one having more teeth than the other, driven by said worm, a dial driven by one of said gears, a dial concentric with said first mentioned dial 20 driven by the other of said gears, said dials having depressions formed therein adapted to be brought into alignment, a cutter operative to sever the thread traveling over said measuring pulley, a catch adapted to render the cutter inoperative, a lever adapted to release the catch, a support pivoted on said lever, a pair of aligning pins depending from said support, said projections being adapted normally to rest on the surface of 30 said dials and retain said lever inoperative and adapted, when said depressions in said dials are in alignment, to drop therein and permit said lever to move to release said catch and means for supporting the elements 35 of the device in operative relationship.

12. In a device for measuring thread, a measuring pulley adapted to be rotated by a traveling thread, a worm driven by said pulley, a pair of gears, one having more teeth than the other, driven by said worm, a dial driven by one of said gears, a dial concentric with said first mentioned dial 45 driven by the other of said gears, said dials having depressions formed therein adapted to be brought into alignment, a spring-actuated cutter operative to sever the thread 50

traveling over said measuring pulley, a spring-actuated catch adapted to render said cutter inoperative, a lever adapted to release said catch, a support pivotally secured to 55 said lever, a spring connected to said support and lever, a pair of pins depending from said support, said pins normally resting on the surface of said dials respectively and preventing said lever from releasing 60 said catch and adapted, when said depressions in said dials are in alignment, to drop therein and permit said lever to release said catch and means for supporting the elements of the device in operative relationship. 65

13. In a device for measuring thread, a measuring pulley adapted to be rotated by a traveling thread, a worm driven by said pulley, a pair of gears, one having more 70 teeth than the other, driven by said worm, a dial driven by one of said gears, a dial concentric with said first mentioned dial driven by the other of said gears, said dials having depressions formed therein adapted 75 to be brought into alignment, a spring-actuated cutter operative to sever the thread traveling on said measuring pulley, a spring-actuated catch adapted to render said cutter inoperative, a lever adapted to release said catch, a brake adapted to stop said pulley, means operated by said cutter through a slot and pin connection for operating said brake after severance of the thread traveling over said pulley by 80 said cutter, a support pivotally secured to said lever, a spring connected to said support and arm, a pair of pins depending from said support, said pins normally resting on the surface of said dials respectively 85 and preventing said lever from releasing said catch and adapted, when said depressions in said dials are in alignment, to drop therein and permit said lever to release said catch and means for supporting the elements 90 of the device in operative relationship. 95

In testimony of which invention, I have hereunto set my hand, at Philadelphia, Pa., on this 12th day of July, 1923.

EDWARD A. HILL.
